Primary Examiner — Lakiya G Rogers*Assistant Examiner* — Altaira J Swangin(74) *Attorney, Agent, or Firm* — Bayramoglu Law Offices LLC**CLAIM**

The ornamental design for a coffee pod storage drawer, as shown and described.

DESCRIPTION

FIG. 1 is a rear, left and top perspective view of a coffee pod storage drawer showing my new design;

FIG. 2 is a right side elevational view thereof; a left side elevational view thereof is a mirror image of the right side elevational view;

FIG. 3 is a rear elevational view thereof;

FIG. 4 is a front elevational view thereof;

FIG. 5 is a top plan view thereof;

FIG. 6 is a bottom plan view thereof; and,

FIG. 7 is a front top left perspective view in a state of use. The broken lines shown in the drawings depict portions of the coffee pod storage drawer that form no part of the claimed design.
